US0D1043758S

(12) **United States Design Patent** (10) Patent No.: **US D1,043,758 S**
(45) Date of Patent: ** Sep. 24, 2024

(54) **PUMP FOR LIQUIDS**

- (71) Applicant: **J. Wagner GmbH**, Markdorf (DE)
(72) Inventor: **Stephan Bader**, Oberteuringen (DE)
(73) Assignee: **J. Wagner GmbH**, Markdorf (DE)
(**) Term: **15 Years**
(21) Appl. No.: **35/515,656**
(22) Filed: **Nov. 10, 2022**

(80) **Hague Agreement Data**

Int. Filing Date: **Nov. 10, 2022**
Int. Reg. No.: **DM/224863**
Int. Reg. Date: **Nov. 10, 2022**
Int. Reg. Pub. Date: **Nov. 25, 2022**

(30) **Foreign Application Priority Data**
